UNITED STATES PATENT OFFICE.

THOMAS WHEATLEY, OF SYRACUSE, NEW YORK.

AIR-VALVE.

SPECIFICATION forming part of Letters Patent No. 566,954, dated September 1, 1896.

Application filed April 29, 1895. Serial No. 547,561. (No model.)

To all whom it may concern:

Be it known that I, THOMAS WHEATLEY, of Syracuse, in the county of Onondaga, in the State of New York, have invented new and useful Improvements in Air-Valves, of which the following, taken in connection with the accompanying drawings, is a full, clear, and exact description.

My invention relates to improvements in combination, positive, and automatic air-valves, particularly applicable for use upon radiators, coils, &c., containing steam or other circulating mediums, and has for its object the production of an economically-manufactured and attractive device capable of either automatic or positive operation, which consists of a minimum number of parts, is readily adjusted, prevents the escape of the water of condensation, and is highly effective and durable in use; and to this end it consists, essentially, in the construction and arrangement of the parts of the valve, all as herein-after more particularly described, and pointed out in the claim.

In describing this invention reference is had to the accompanying drawings, forming a part of this specification, in which like letters indicate corresponding parts in both the views.

Figure 1 is a vertical section of a portion of a pipe or steam-chamber and an elevation of my improved valve operatively secured thereto; and Fig. 2 is a longitudinal section of the detached valve, illustrating its general construction and arrangement.

As is well known, when steam is discharged into a coil or radiator it is partially condensed by contact with the cold walls, and the condensation trickles down the inside of the coil or radiator and is readily discharged with the outgoing air through an air-valve connected to the coil or radiator. Various float-valves have been devised for preventing the escape of the water of condensation, but these valves are more or less complicated and expensive, are liable to discharge more or less water before operating to prevent its escape, and are quite readily deranged and rendered inoperative. Air-valves have also been formed with attaching-nipples having their extremities tapered for preventing the escape of the water of condensation, but in the practical op-

eration of such valves the water runs along their pointed extremities, and, when passing over the end thereof, is blown into the nipples. 55

My present invention is of such construction that the water of condensation, following the inner wall of the coil or other steam-chamber to which it is connected, is positively prevented from escaping therethrough with the outgoing air.

My improved valve is formed with a suitable inclosing shell A, provided with a flange or shoulder a, projecting from its outer face, and an internal lengthwise chamber a'. One 65 end of the chamber a' is open, and its opposite end is provided with a valve-seat a², surrounding an inlet-port a³. One end of a suitable outlet-port a⁴ is arranged adjacent to the seat a², and its other end discharges through 70 the flange or shoulder a. The shell A is attached to a radiator or other steam-chamber B (partly illustrated at Fig. 1) by a suitable nipple A', which projects beyond the inner face of the adjacent portion of the wall of the 75 chamber B, and is provided with a lengthwise inlet-passage a⁵, extending from its end face and discharging into the port a³.

The base of the nipple A' is preferably screw-threaded for facilitating its securement, and the free extremity of said nipple is gradually decreased in diameter toward its end face. An annular groove a⁶ is formed in the outer face of the nipple A' between its opposite extremities, and this groove operates 85 to receive any moisture passing down the adjacent wall of the radiator or steam-chamber B. The outer shoulder a⁷ of the groove a⁶ prevents the passage of said water to the end face of the nipple A', and consequently it is 90 not discharged with the outgoing air through the passage a⁵, but readily falls from the groove a⁶ to the base of the chamber B. A nipple of this peculiar construction, although quite simple and economically manufactured, 95 is particularly efficient for effecting a very important result—viz., prevention of the outward passage of the water of condensation through the air-valve—and forms an important feature of my invention.

A cap A² is used for closing the open end of the inclosing shell A and forms a support for a valve-piece A⁸, presently described. One end of the cap A² is suitably secured to

the outer face of the adjacent end of the shell A, as by screw-threads, and is movable against the annular shoulder a , which limits the movement of said cap and prevents compression 5 or injury of the valve-piece A³ as the cap A² is adjusted lengthwise. The opposite end of the cap A² projects beyond the shell A and is formed with an internal chamber a⁸ of substantially the same diameter as the chamber 10 a' of the shell A. An expansible valve-piece A³, formed of any suitable expansible material, is loosely mounted within the chambers a' a⁸, so that its entire length is subjected to the action of the steam admitted within said 15 chambers through the port a³.

One end of the valve-piece A³ is movable against the valve-seat a² for closing the port a³ and preventing the entrance of steam within the chambers a' a⁸, and its opposite end is 20 engaged by a suitable adjusting-screw A⁴, movable in the end wall of the cap A². This screw A⁴ is preferably formed with a contracted engaging end, and is set when the valve-piece A³ is expanded and is in engagement 25 with the seat a², whereupon the valve-piece A³ then contracts and expands automatically to control the passage through the port a³. When desired to use my invention as a positive valve, the cap A² is screwed out- 30 wardly from the shell A, and when again engaged with the shoulder a the valve is in condition to operate automatically without

necessitating additional adjustment of the screw A⁴.

It will be readily understood that as the cap 35 A² is rotated all liability of revoluble movement of the valve-piece and consequent injury to its end in engagement with the seat a² is obviated, as the valve-piece is loosely mounted within the chambers a' a⁸, and the cap A² is free to turn without revolving the valve-piece A³.

Having thus fully described my invention, what I claim as new, and desire to secure by Letters Patent, is—

The combination with a steam-chamber; of an air-valve secured to the chamber and provided with an attaching - nipple passage through the wall of the chamber and projecting beyond its inner face, said nipple being formed with an inlet-passage extending from its free extremity and an annular groove in its outer face interposed between its opposite extremities, substantially as and for the purpose described.

In testimony whereof I have hereunto signed my name, in the presence of two attesting witnesses, at Syracuse, in the county of Onondaga, in the State of New York, this 19th day of April, 1895.

THOMAS WHEATLEY.
